CLAIM

The ornamental design for a daytime running light arrangement, as shown and described.

DESCRIPTION

FIG. 1 is a front left elevated view of a daytime running light arrangement for a vehicle;

FIG. 2 is a front left perspective view thereof;

FIG. 3 is a front view thereof;

FIG. 4 is a left side view thereof;

FIG. 5 is top view thereof;

FIG. 6 is another front view thereof, but mounted on a vehicle to show environmental structure, the vehicle being unclaimed and shown in broken lines; and,

FIG. 7 shows a variation thereof, with the same daytime running light arrangement on the left side, as shown in FIG. 6, plus a mirror image daytime running light arrangement shown also on the right side of the same unclaimed vehicle, with the unclaimed vehicle shown in broken lines.

The broken lines in FIGS. 1-5 depict boundaries of the daytime running light arrangement and form no part of the claimed design. Features of the head light shown de-emphasized in half-tones represent environmental subject matter that forms no part of the claimed design.
